UNITED STATES PATENT OFFICE.

GEORGE E. BECK, OF TOLEDO, OHIO.

GUY-ANCHOR.

1,081,654.

Specification of Letters Patent. Patented Dec. 16, 1913.

Application filed January 22, 1913. Serial No. 743,447.

To all whom it may concern:

Be it known that I, GEORGE E. BECK, citizen of the United States, residing at Toledo, in the county of Lucas and State of Ohio, have invented certain new and useful Improvements in Guy-Anchors, of which the following is a specification.

This invention relates to devices employed for anchoring guy cables or rods, and adapted to be employed for holding telegraph, telephone, trolley wire poles and the like, smoke stacks, derricks, and any other object or structure requiring guy wires, and has for one of its objects to simplify and improve the construction and increase the efficiency and utility of devices of this character.

Another object of the invention is to provide a simply constructed device which may be readily applied and effectually supports the guy wires in the ground.

With these and other objects in view the invention consists in certain novel features of construction as hereinafter shown and described and then specifically pointed out in the claims, and in the drawings illustrative of the preferred embodiment of the invention.

Figure 1 is a side elevation of one of the improved devices with the anchor plates in closed position. Fig. 2 is a perspective view from beneath of the traveler plate. Fig. 3 is a perspective view from above of the lower or holding plate. Fig. 4 is a sectional detail with the anchor plates in open position. Fig. 5 is a plan view of the parts as shown in Fig. 2.

Corresponding and like parts are referred to in the following description and indicated in all the views of the drawings by the same reference characters.

The improved device comprises a rod 10 of any suitable size and of any suitable strength and with means, such as an eye 11, at one end for the attachment of a guy member and threaded at the opposite end as represented at 12. At its lower end the rod 12 extends through a holding or base plate 13 and is provided with a nut 14 bearing beneath the plate. The rod is thus rotatable in the plate 13, and the latter is formed with a plurality of radial sockets 15. Any required number of the sockets may be employed, but generally four will be used as shown.

Threaded upon the rod 12 is a traveler

plate 16 which is likewise provided with a plurality of radial sockets 17 corresponding in number to the sockets 15.

The anchor plates are represented conventionally at 18 and correspond in number to the sockets, and each plate is provided with a rib 19 upon its lower face which is extended at 20. The plates 18 may be of any required shape, but are preferably pointed and slightly curved outwardly as shown, and likewise decrease in thickness toward the pointed ends. Pivoted at 21 in each of the sockets 15 is a link 22, each link being forked at its outer end and bearing upon opposite sides of one of the ribs 19 and pivoted thereto at 23. The plates 18 are so arranged that when the rod 10 is rotated in one direction to cause the plate 16 to be moved to its farthest point from the plate 13 the plates 18 will be caused to assume a position substantially at right angles to the plate 16, or to occupy the least possible space transversely, and then when the rod 10 is rotated in the opposite direction the plate 16 will be moved toward the plate 13 with the result of causing the links 22 to distend the plates 18 into position substantially in alignment with the transverse axis of the plate 16.

When the improved anchor is to be applied a hole is bored in the ground corresponding in area to the plate 16, and the anchor device with the anchor plates 18 in withdrawn position are inserted into the hole in the ground to a sufficient distance and the rod 10 then rotated to cause the plates 18 to be expanded into the ground, the whole assuming a position as shown in Fig. 4, the anchor plates 18 being thus forced into the ground and effectually anchoring the device therein.

The improved device may be constructed of any required size or strength to correspond to the structure with which it is to be employed and will be constructed entirely of metal, and will preferably be galvanized or otherwise protected from corrosion.

Having thus described the invention, what is claimed is:

1. In a device of the class described, a threaded rod, a step member in which said rod is rotatably mounted, a traveler threaded upon said rod above said step member, anchor plates swinging upon said traveler and covering and protecting the step member

and coupling means between said anchor plates and step member.

2. In a device of the class described, a threaded rod, a step member in which said rod is rotatably mounted, a traveler threaded upon said rod above said step member and having a plurality of radial sockets, an anchor plate mounted to swing in each of said sockets and formed with its lower end

curving outwardly, and links coupling said anchor plates respectively to said step member.

In testimony whereof I affix my signature in presence of two witnesses.

GEORGE E. BECK. [L.S.]
